UNITED STATES PATENT OFFICE.

EMILE ERICSON, OF PELHAM, AND ROGER WEISS, OF FLATBUSH, BROOKLYN, NEW YORK,
ASSIGNORS TO C. R. WHITING CO., A COPARTNERSHIP CONSISTING OF VICTOR
FRIEDLANDER AND FRANK V. FRIEDLANDER, BOTH OF NEWARK, NEW JERSEY.

DESIGN FOR PAPER OR SIMILAR ARTICLE.

Application filed December 6, 1923. Serial No. 7,956. Term of patent 3½ years.

To all whom it may concern:

Be it known that we, EMILE ERICSON and ROGER WEISS, citizens of the United States of America, the said EMILE ERICSON residing at Pelham, in the county of Westchester, State of New York, and the said ROGER WEISS residing at Flatbush, in the borough of Brooklyn, city and State of New York, have invented a new, original, and ornamental Design for Paper or Similar Article, of which the following is a specification, ref-

erence being had to the accompanying drawing, forming part thereof, and which shows a plan view of a sheet of paper or similar article bearing our design.

We claim:

The ornamental design for paper or similar article as shown.

Dated at New York this 2d day of Nov., 1923.

EMILE ERICSON.
ROGER WEISS.
